UNITED STATES PATENT OFFICE.

FRED A. DENNETT, OF SHEBOYGAN, WISCONSIN.

DESIGN FOR A BENT-WOOD CHAIR-SEAT.

SPECIFICATION forming part of Design No. 27,595, dated August 31, 1897.

Application filed May 15, 1897. Serial No. 636,798. Term of patent 14 years.

To all whom it may concern:

Be it known that I, FRED A. DENNETT, a citizen of the United States, residing at Sheboygan, in the county of Sheboygan and State 5 of Wisconsin, have invented and produced a new and original Design for Bent-Wood Chair-Seats; and I do hereby declare the following to be a full, clear, and exact description of the same, reference being had to the accompanying drawings, forming a part thereof.

In the said drawings, Figure 1 is a longitudinal vertical section, Fig. 2 is a transverse vertical section, and Fig. 3 is a perspective view, of a bent-wood chair-seat embodying my 15 new design.

My design relates to the new and original shape or configuration of the article.

The leading feature of this design for a bent-wood chair-seat consists in the peculiar shape 20 of the top or upper portion A thereof, which, starting from the points *a a*, is first curved downward and forward on a shallow or gradual concave line, forming the arc of a large circle, to the points *b b*, and thence continued 25 forward on the line of a very shallow ogee to the points *c c*, and then finally carried down and around on an abrupt curved convex line to the points *d d*, forming the arc *c d* of a much smaller circle than that of the arc *a b* 30 first named.

A minor feature of this design lies in the peculiar shape of the lower or side pieces B. The upper surface of the side piece B conforms in shape exactly to the described curved configuration of the said portion A, and the 35 central or main portion of the under side of said piece B, between the points *e f*, corresponds to the shape of the upper surface above the same. From the point *f* to the point *g* the said under side follows the line of 40 a true ogee, and from the point *g* to the forward point *d* the said under side is nearly straight, while from the point *e* to the point *h* the said under side follows the line of an ogee shorter and smaller than the ogee between the points *f g*, and from the point *h* to the rear point *a* the under and rear side of the rear end of the side piece B is drawn on a curved line, as shown.

Having described my invention, what I 45 claim as new, and desire to secure by Letters Patent, is—

The design for a bent-wood chair-seat, as herein shown and described.

In testimony whereof I affix my signature 50 in presence of two witnesses.

FRED A. DENNETT.
